UNITED STATES PATENT OFFICE.

KARL KIEFER, OF CINCINNATI, OHIO.

FILLING MACHINE.

Application filed February 20, 1919. Serial No. 278,287.

To all whom it may concern:

Be it known that I, KARL KIEFER, a citizen of the United States, and a resident of Cincinnati, in the county of Hamilton and State of Ohio, have invented certain new and useful Improvements in Filling Machines, of which the following is a specification.

My invention relates to apparatus for filling successively relatively large numbers of containers, and more especially to apparatus such as that of my Patent No. 1,313,301, dated August 19, 1919, for filling such containers with semi-solid substances that do not flow appreciably, under pneumatic pressure or action of gravity in the filling passages, such as stiff butters, pastes, ointments and the like.

The object of my invention is to simplify the construction of such apparatus, and to facilitate the filling of certain kinds of substances of the character just mentioned better than is possible with my prior invention just mentioned; especially such substances as contain particles of solid matter, such as seeds or pits and the like which are crushed by the gears and clog or break the mechanism in said prior invention. A further object is to provide for filling containers of a relatively wide range of sizes by means of comparatively simple mechanism. Another object is to facilitate the lubrication of the parts of the machine with which the filled substance must come in contact. Other objects will appear in the course of the ensuing description.

In the drawings:

Fig. 1 is a partial side elevation of a machine embodying my invention;

Fig. 2 is a plan view of the same;

Fig. 3 is a front end elevation of the same, i. e., looking to the right in Fig. 1 or Fig. 2;

Fig. 4 is a partial longitudinal vertical section, enlarged, on a plane corresponding to the line 4—4 of Fig. 3;

Fig. 5 is a vertical cross-section of the discharging element and the distributing element of the filling head on a plane corresponding to the line 5—5 of Fig. 2; and

Fig. 6 is a detail side elevation of one of the plungers.

As I prefer to construct my invention, there is a base 1 preferably mounted on rollers as shown, and which supports, at a convenient height, a table 2, near one end of which is fixed the upright bearing hub

3 extending above and below the table and forming the bearing for the upright shaft 4 which is supported therein by the sprocket-wheel 5 fixed to the shaft and bearing on the top of the hub 3, and extends below the hub with the bevel gear 6 fixed thereto. A bevel pinion 7 meshes with the gear 6 and is on a horizontal shaft with the spur gear 8, which in turn meshes with the spur pinion 9 on the shaft with the driving pulley 10 which is turned by any suitable means, as by the electric motor 11 through the medium of the belt 12. Where the electric motor 11 is used, it is preferably mounted on a standard 13 some distance above the rest of the machine where it is not exposed to moisture coming from the machine parts.

The filling head comprises the distributing element 14 and discharging element 15; the one being above and the other below, and these elements having flat faces bearing together and being suitably held tightly together by clamping collars 16 on a threaded neck 17 of the discharging head which extends up through the hub 18 of the distributing head. These parts are held at any desired height on the shaft 4 by means of lock-nuts 19 and 20, Fig. 3, lock nut 20 bearing against the lower end of the discharging element 15, and lock nut 19 bearing upon the upper end of the neck 17, respectively.

The discharging head has, down through it, four orifices or spouts 21 spaced at equal intervals therearound, and its neck 17 is rotatable in the hub 18 of the distributing element 14, which latter is held stationary by a stay 22 projecting from it against a post 23 fixed upright in the table 2 just to the rear of these parts. The discharging head is made to turn with the shaft 4 by the clamping pressure of the nuts 19 and 20, and also, preferably, by a key 24 fitting in a keyway 25 in the shaft 4 (Fig. 3.)

The distributing element 14 has at the right side, an inlet nipple 26 leading radially inwardly and then down and around the element into a segmental channel 27 opening through the bottom of the distributing element against the close fitting upper face of the discharging element. This channel is located so that the orifices 21 successively register with it during the relative movement of these elements 14 and 15.

As a means to force substance into the inlet 26 of the distributing element 14, I provide a double-acting reciprocating pump

which comprises the two alined cylinders 28 and 29 opening forwardly and rearwardly along the machine with their closed ends toward each other, and having between these closed ends a lateral discharge outlet port 30 opening downwardly through the lower face of the pump structure. Communicating ports 31 and 32 lead from the closed ends of the cylinders 28 and 29, respectively, 5 in toward the outlet port 30 and also open downwardly through said face of the pump structure short distances to the front and rear, respectively, of the downward opening of said port 30. This lower face of the pump structure thus having these three ports 30, 31 and 32 opening downwardly through it, is made flat, and a slide-valve element 33 has a flat upper face bearing up against said lower face of the pump structure 10 and is guided for movement longitudinally of said face by a bottom element 34 bolted to the pump structure astraddle of the element 33 and enclosing a space below said element 33 into which leads the inlet or supply port 35.

The element 33 has two ports 36 and 37 extending entirely through it and of width and length corresponding to the downward openings of the ports 31 and 32; and between these ports 36 and 37 is a longer port 38 which, however, does not extend entirely through the element 33. These ports 36, 37 and 38 are so spaced along the element 33, and the longer port 38 is of such length that 15 when one of the ports, as the port 36 in Fig. 4, is registering with the opening of the port 31, the longer port 38 is registering with the port 32 and also with the downward opening of the outlet port 30. In the extreme reverse position of this element 33, port 37 would register with the port 32 while the longer port 38 would open communication between the port 31 and the port 30.

The shaft that carries the bevel pinion 7 to drive the upright shaft 4 also carries, in addition to the spur-gear 8 before mentioned, a spur gear 39 meshing with an intermediate gear 40, which in turn meshes 20 with a gear 41 on the crank shaft 42 which is journaled transversely of the machine across the top of the pump structure at its middle. This crank shaft 42 carries the crank 43 which has a wrist-pin 44 radially adjustable in the crank by means of a screw 45 and nut 46 (Fig. 1.) A slide-bar 47 is mounted in horizontal guides on the top of the pump structure and extends past the opposite open ends of the cylinders 28 and 29, and has fixed on it, near one end, the laterally projecting stud 48 out over the guides of the rod 47. A connecting rod 49 is pivoted to this stud 48 and to the wrist-pin 44. These parts are at the right-hand 25 side of the machine, while the train of gears

just described are at the left-hand side. The cross-heads 50 and 51 are clamped on the opposite projecting end parts of the bar 47. Each cross-head comprises the main part 52 extending up astride the bar 47 and 70 having bolted to it the clamping plate 53 down on top of the bar. Extending down from the main part 52 the cross-head has the pedestal 54. These pedestals 54 of the cross-heads 50 and 51 have fixed in them the 75 outer ends of the plunger rods 55 and 56, respectively, which have their inner ends fixed in the plungers 57 and 58, which snugly fit the bores of the cylinders 28 and 29, respectively.

Fastened to the inner side of the gear 41 at the left is the cam 59 which has in its face the slot 60 opening over toward the pump structure. This slot is continuous around the face of the cam and for part of 80 its extent lies farther from the center than it does in another part of its extent, and the major proportion of each one of these parts being concentric to the shaft 42; the parts joining each other by rather sharp inclines. 85 This cam is clearly indicated by the dotted lines in Fig. 4.

A bell crank comprising the short arm 61 and the long arm 62 has the fulcrum 63 in one side of the pump structure immediately to the rear of the cam 59 and gear 41; the short arm 61 having a projection 64 in the cam groove 60 and the longer arm 62 extending down alongside the pump structure and having its free end connected by a short link 65 to the rearwardly projecting part of the slide-valve element 33, as also clearly shown by the dotted lines in Fig. 4.

On the top of the table 2 is mounted the carrier frame 66, the front end of which is substantially a semi-circle concentric with the shaft 4. This frame extends back from this front end as far as may be desirable, and has the semi-circular rear end, on the bottom of which is supported the bearing 67 for the upright shaft 68 which has journaled on it the rear sprocket-wheel 69, in the same horizontal plane as the front sprocket-wheel 5 previously mentioned as being mounted on the shaft 4. The sprocket chain 70 passes around these sprocket wheels, and carriers in the form of trays 71 are mounted at intervals on this chain, which travels inside the carrier-frame 66 with the trays sliding along the upper sides of this frame. The sprocket-wheel has suitable recesses 72 to accommodate the mountings of the carriers or trays 71 on the chain as they pass around the wheels. This construction is clearly disclosed and claimed in my co-pending application hereinbefore referred to and need not be further elucidated herein. It is sufficient for the present purpose to note that these trays 71 are open on their radially outward sides so that con-

tainers placed on them will readily slide off radially onto a suitable conveyor 73 at the left side of the machine at the rear of the table 2 (Fig. 2.) As here shown, this conveyor 73 comprises a chain 74 suitably driven around a shaft 75 to travel rearwardly from the machine, as indicated by the arrow in Fig. 2. As any suitable conveyor may be used, and the one here shown is not peculiar to my invention, it need not be further described.

The carriers 71 are mounted at such intervals on the chain 70 that where they pass around the sprocket wheel 5 they will be ninety degrees apart around said wheel, and the parts are so proportioned that each tray will come substantially under one of the orifices or spouts 21 of the discharging element 15, and while traveling in the semi-circle at the front, will remain under such orifice or spout.

The carrier-frame 66 and other parts just described are preferably so proportioned that with this spacing of the carriers 71 there will be an uneven number of them in the endless carrier system thus made up. For instance, as shown herein, and as clearly seen in Fig. 2, there are thirteen of these carriers or trays 71. The withdrawing element 76 comprises two curved arms projecting in diametrically opposite directions from the top of the hub of the rear sprocket-wheel 69. Preferably, this element 76 is mounted on this hub by fitting down on two pins 77 in the hub, so that it may be readily withdrawn from these pins, but will turn with the wheel 69 when held thereon. The arms of this element 76 are of such length and so shaped that as an arm swings past a tray or carrier 71 that is coming tangentially onto the wheel 69 in its backward travel at the left of the machine, the arm will push a container A (Fig. 2) to the left onto a receiving part of the conveyor 73. As successive ones of these containers A are pushed off, they push the preceding ones ahead onto the chain 74 which may convey them to any desired destination or to receive any further operation required. With the uneven

number of trays 71, and the displacing element 76 having its arms spaced around the sprocket-wheel 69 twice the angular distance that the trays 71 are spaced, each one of the arms will swing past a given tray 71 only once during each two circuits of the carrier. The result is that a container on a given tray will be carried around the circuit twice before it is displaced by the element 76.

If the element 76 would have two additional arms placed at right angles or a total of four arms instead of two, every one of the trays will be swept by an arm of the withdrawing element at every passage around the circuit, and a container placed on a given tray will pass around the circuit

only once. Or, if an element 76 would have only one arm, each container will pass around four times. It will be understood that any number of trays may be used in the system or different degrees of angular spacing may be given to the trays where they pass around at the ends of the system; with any even number of arms and any odd number of trays, or vice versa, in any such system, the number of times the container will pass around being as the number of trays around a circle to the number of arms on the withdrawing element.

The conveyor 73 has a lateral guide-bar 78, and the carrier system has a guide bar 79 in a head 80 adjustable up and down on a post 81 in the table 2 at the right of the filling head.

The relatively movable parts which are exposed to the substances that are filled into the containers are preferably lubricated with water. A reservoir 82 is mounted on the front end of the table 2 with a distributing pipe 83 extending downward and back along the right-hand side of the pump and other mechanism below the table 2. A flexible branch pipe 84 leads to the interior of the bottom element 34 to admit water in the guide of the slide-valve element 33. Similar branch pipes 85 and 86 lead into the cross-heads 50 and 51 where they communicate through ports 87 with pipes 88 that lead into longitudinally and then upwardly extending ports 89 (Fig. 4) in the plungers 57 and 58, respectively. Each plunger preferably has three circumferential grooves 90, 91 and 92. The groove 90 near the inner end of the plunger affords a collecting place for some of the substance being filled, which thus acts somewhat as a gasket. The port 89 leads up through the wall of the plunger into the middle groove 91 at the top of the plunger. A longitudinal groove 93 leads at the bottom of the plunger from the groove 91 to the groove 92 near the outer end of the plunger; and at the top another short longitudinal groove 94 leads from the groove 92 out through the outer end of the plunger. Where these flexible branch pipes 84, 85 and 86 lead from the distributing pipe 83, they preferably do not communicate directly with the interior of said pipe 83, but have small basins 95 at their upper ends under small downwardly extending nipples 96 controlled by stop-cocks 97. Sufficient lubrication is provided by adjusting these cocks 97 so that the water drips from the nipples 96 into the basins 95, from which it runs down through the flexible pipes or tubes to the parts to be lubricated.

The upper flat surface of the discharging element 15 preferably has in it two annular grooves 98 and 99 concentric with the shaft 4, and lying respectively radially inside and

outside the orifices 21. A shallow cup 100 is formed on the upper side of the distributing element 14 with perforations 101 and 102 down through the element 14 to these 5 grooves 98 and 99. A small quantity of water placed in this cup serves to lubricate the contacting surfaces of the elements 14 and 15.

A flexible pipe or hose 103 connects to the 10 outlet port 30 and leads out and up along the right-hand side of the machine into the nipple 26 of the distributing element. A pipe 104 leads into the inlet port 35 from the left-hand side of the machine. The 15 inlet port 35 is provided with a drain-cock 105.

The supply pipe 104 is preferably connected with a source of supply of the substance to be filled into the containers located a considerable distance above the machine; so that the substance enters the pump inlet under considerable pressure due to gravity. This adds to ease of operation of the machine; since the pump with its opposed 25 plungers and slide-valve tends to be operated by this pressure. In fact, with a freely flowing liquid under sufficient pressure, this pump would operate as a hydraulic motor. It will be understood 30 that this is not essential but only desirable as permitting the electric motor 11 or other motive device to be of moderate size and require only a moderate amount of energy for driving the machine.

35 The motor 11 turns the driving pulley 10 over to the rear of the machine, as indicated by the arrow at the top of Fig. 4. This results, through the medium of the bevel gears, in driving the sprocket-chain 70 and carriers or trays 71 around from right to left at the front of the machine; these traveling forward at the right and rearwardly to the conveyor 73 at the left, as indicated by the arrows in Fig. 2. 45 This, at the same time, through the medium of the chain of gears, turns the cam 59 and crank 43 over forwardly, as indicated by the arrow in Fig. 4.

The machine is shown in the drawings as 50 being at a stage of its operation in which one of the orifices 21 in the discharging element 15 and the tray 71 thereunder has traveled half the length of the channel 27 in the distributing element 14; and the pump plungers 57 and 58 are midway of their stroke. 55 This channel 27 is slightly shorter than the distance between the adjacent edges of any two adjacent orifices 21; so that communication is cut off between a preceding orifice 60 and the channel before communication begins between said channel and a succeeding orifice. This makes it impossible for any of the filled substance remaining in the orifice to be released as it would be by inlet of air 65 through a succeeding orifice opened before

this preceding orifice was completely closed. During the short interval that the channel 27 communicates with neither one of the two adjacent orifices, the discharge from the pump is, of course, cut off; and it will be remembered that these semi-fluid substances are like any liquid in that they are virtually incompressible. The flexible pipe or hose 103 distends slightly to compensate for any slight increase in pressure on the substance passing therethrough; but by properly relatively positioning the pump parts and the distributing-head parts, practically no increase in pressure occurs incident to this temporary complete cutting off of the discharge. This is accomplished by relating the parts as shown, whereby the discharging plunger will have almost reached the inner end of its stroke when this complete cutting off occurs, i. e., the connecting-rod 49 will then be passing "dead center" with the crank 43, and the travel of the plungers for some time will be practically negligible. The gearing is such that each one of the plungers makes an inward stroke while some one of the orifices 21 is passing the channel 27. The velocity of the plunger throughout its stroke is, of course, variable; but since the discharge from each orifice will take place during one of the strokes, and the total amounts delivered at every stroke are uniform, then each container on a respective tray 71 will receive an equal amount of substance.

The machine may be adjusted to deliver 100 a greater or less uniform amount at each stroke by adjusting the wrist 44 along the crank 43 by means of the screw 45 and nut 46; and correspondingly adjusting each 105 one of the plungers 57 and 58 along the bar 47 by loosening the clamping plates 53 of the cross-heads 50 and 51 and moving them inward or outward along the bar 47 until the attached plungers 57 and 58 have the 110 desired very slight clearance at the inner ends of their strokes, then tightening the plates 53.

Any delivered amount for which the machine is thus adjusted is doubled by substituting the two-arm displacing element for the four-arm displacing element; or increased four times by substituting the one-arm element. Thus, the machine may fill 115 containers of a wide range of capacities from a very small fraction of the total capacity of each cylinder up to several times the capacity of each cylinder.

The filling head comprising the elements 14 and 15 may be adjusted up and down on the shaft 4 as before described to bring its discharge orifices 21 close over the tops of containers of different heights; and trays or carriers 71 of different sizes may be readily placed on the machine for containers of different diameters. These adjustments are in 120 125 130

accordance with my co-pending application hereinbefore referred to; the distinction between the present invention and the one in said application being more particularly 5 found in the different kind of forcing means and the differences in the filling head and carrier system incident thereto.

This forcing means which does not compel the substance to pass through any very restricted 10 passage at any part of its travel is especially adapted for avoiding the crushing of solid particles in the substance, as, for instance, seeds, pits and the like in fruit butters and similar preparations. This advantage 15 is further realized by having the pump horizontally acting and having its discharge ports 31 and 32 at the lower sides of the cylinders. Such solid and more dense particles gravitate to these ports and are not frequently 20 caught between the inner ends of the plungers and the closed ends of the cylinders, when the clearance of these plungers is made very slight, as is desirable. It is not necessary, however, that this clearance 25 should be exceedingly small, and it is entirely practicable to increase the clearance where there are large solid particles in the substance being filled.

The water lubrication insures easy working 30 of the machine even with the most viscid substances. No special provision is made for carrying off the lubricating water, since the discharge thereof is practically negligible because so little of the water is required. It 35 will be understood that the travel of this lubricating water around the plunger is in both directions from the port 89 down around the middle groove 91, thence out along the groove 93 into the groove 92 and 40 in both directions up around this groove 92, under the slight "head" of water in the tube 85 or 86, and out through the terminal groove 94 at the top of the plunger into the outer end of the cylinder. The inlet of this 45 water to the tubes 84, 85 and 86 by dripping from the nipples on the pipe 83 permits of a very slow feeding of the lubricating water, while at the same time permitting a solid column of water in each one of the tubes 84, 50 85 or 86 which will thus slowly but steadily flow out between the parts to be lubricated.

By confining the pump below the carrier system, any leakage from it is kept away from the carriers and the containers thereon. 55 There is practically no leakage from the distributing head; and the filling of the container is accomplished in but little more than one-third of the semi-circular travel during which the orifice is over the container, so 60 that the remainder, or almost two-thirds of this travel, is left for whatever drippage there may be from the orifice, which will thus be caught in the container. Practically all of the substance that is not forced out of 65 the orifice during its communication with

the channel 27 is held up in the orifice by atmospheric pressure, so that this drippage is relatively very slight.

This retention of the substance in the orifice by atmospheric pressure is facilitated by 70 having the orifice relatively small in cross-sectional area. This is made practicable by proportioning the forcing means or pump so that even at its greatest stroke it does not force the substance too rapidly through the 75 relatively small orifices; the filling of large sized containers being accomplished by repeated passage under the filling head as hereinbefore described, rather than by making the pump larger with the necessary corresponding 80 increase in cross-sectional area of the outlets of the orifices 21.

Some substances which are very viscid or "stringy" and therefore do not drop cleanly 85 away from the orifices 21 are more practically managed by emptying each orifice 21 entirely of the material after it passes the end of the channel 27. For this purpose, the distributing element 14 may have an opening 106 (shown by dotted lines in Fig. 2) just 90 past the end of the channel 27 to admit air to the orifice 21 coming thereunder, which may be merely under atmospheric pressure or may be of a higher pressure supplied 95 through a pipe 107.

All of the parts exposed to the substance are readily cleaned by merely admitting hot water to the machine while it is operated. It is, therefore, not frequently necessary to have access to the interior parts. But the 100 filling head is readily taken apart by loosening the nut 19 and collars 16, and either plunger 57 or 58 is readily removed by loosening it from the bar 47, as before described, while ready removal of the slide-valve element is possible upon disconnecting it from the link 65 that connects it to the bell-crank arm 62. Those bearings of the machine with which the filled substance does not come in contact are lubricated with oil 110 as usual, which is supplied through the various oil cups indicated on the drawings, and which need no particular description.

This machine is described as particularly adapted for filling semi-solid substances; but 115 it will be understood that it is also adapted for filling readily flowing substances, and that the machine is subject to modifications adapting it to different requirements. Therefore, while certain constructional details are deemed preferable in connection 120 with my invention, and I have shown and described these rather specifically in elucidating the construction and use of my invention, as is required, I do not wish to be 125 understood as being limited to such precise showing and description, but having thus fully described my invention, what I claim 130 as new and desire to secure by Letters Patent is:

1. In a filling machine, filling means comprising members continuously moving relatively and provided, respectively, with passages adapted to register, the passage in one member being elongated in the direction of the relative movement, and measuring means having a discharge passage connected with the passage of one of said members and comprising a plunger and a crank causing a complete gradual discharging stroke of said plunger while said passages are in registry. 45
2. In a filling machine, filling means comprising relatively moving members, one member having a succession of passages to discharge into successive containers and the other member having a passage elongated in the direction of relative movement, with which the passages of the one member successively register while traveling along said elongated passage, and double-acting pulsating measuring means having a discharge passage leading to said elongated passage, alternate complete discharging pulsations of said measuring means occurring within the periods of registry of successive passages of the one member with said elongated passage of the other member. 50
3. In a filling machine, filling means comprising members with successively registering passages, the registering passage in one member being elongated and increasing the period of registry, measuring means having a discharge passage connected with said elongated passage and comprising alternately acting plungers each completing a discharge stroke within a period of registry of the passages in the two members. 55
4. In a filling machine, filling means, means for carrying a plurality of containers successively around a circuit under said filling means, and means to withdraw certain of said containers in another part of said circuit, this means and said carrying means being so relatively arranged that each one of said containers is carried around said circuit more than once. 60
5. In a filling machine, filling means, means for carrying a plurality of containers successively around a circuit under said filling means, and means to withdraw certain of said containers in another part of said circuit, this means and said carrying means being so relatively arranged that each one of said containers is carried around said circuit more than once, whereby said filling means deposits an amount of substance in the container each time the container passes around said circuit, and means for varying the amount of substance thus deposited each time. 65
6. In a filling machine, the combination with a filling means including members continuously rotating relatively and provided with passages, respectively, arranged for registry and one of said passages being elongated in the direction of relative movement, of measuring means having a discharge passage for material coming from one of the passages first mentioned and including a plunger, and a crank of readily variable stroke actuating the plunger to force a gradual, complete discharge variable at will. 70
7. In a filling machine, the combination with a filling means including members which continuously move relatively and are provided, respectively, with passages arranged for registration, one of said passages being elongated in the direction of relative movement, of measuring means, having a discharge passage, to supply material to one of the passages first mentioned and including an intermittently moving plunger, and a crank of readily adjustable stroke for actuating the plunger. 75
